UNITED STATES PATENT OFFICE.

HARRY A. STEPHENS, OF MISSOULA, MONTANA.

CLOSURE FOR VESSELS.

1,034,321.

Specification of Letters Patent. Patented July 30, 1912.

Application filed April 23, 1912. Serial No. 692,724.

To all whom it may concern:

Be it known that I, HARRY A. STEPHENS, a citizen of the United States, residing at Missoula, in the county of Missoula and State of Montana, have invented certain new and useful Improvements in Closures for Vessels, of which the following is a specification.

My present invention pertains to improvements in closures for vessels, and has reference more particularly to means for hermetically sealing a jar, and also to the peculiar formation of the cover or closure which tends, as it is positioned, to force out the air from the material contained within the jar, and likewise such air as may be above the material, prior to the sealing of the closure.

The construction also provides a reservoir for the sealing material and, consequently, provides an easy means of introducing the same into the lock between the closure and the body of the receptacle.

The invention is illustrated in the annexed drawings, wherein:

Figure 1 is a sectional elevation of the jar and the closure; Fig. 2 a top plan view thereof, the sealing medium being omitted; and Fig. 3 a detail sectional view of a portion of the upper part of the jar.

In the drawings, 1 denotes the body of the jar, made of any suitable material, and provided with a downwardly-inclined ledge or seat 2, for the cover, said seat preferably projecting inwardly to a slight extent. Formed in the inner wall or face of the jar above the seat is a series of grooves 3.

The cover or closure of the jar is provided at its under face with a rounded projection or protuberance 4, and said face is inclined upwardly and outwardly therefrom, such inclined face being designated by 5. The outer diameter of the closure is less than the internal diameter of the upper inner wall of the jar; or in other words, the edge of the cover stops short of making contact with the wall of the jar, coming to rest upon the seat intermediate the inner and outer edges thereof. The cover or closure is provided with three external rings or channels 6, 7 and 8, the lowermost pair, 6 and 7, being so spaced that when the cover or closure is positioned upon its seat they will stand opposite, or substantially opposite, the grooves or channels 3 formed in the jar. The upper wall of the channel 8 will

preferably stand at a point slightly above the upper edge of the jar, and will thus afford a means whereby a pry may be inserted beneath the said edge when it is desired to remove the cover. The closure is provided in its upper face with a chamber or receptacle 9, adapted to receive and hold a supply of sealing material, such as paraffin, wax or any other suitable material which when cold will set and securely hold the cover in position.

Opening outwardly from the chamber 9 is a series of grooves or channels 10, which are preferably narrower at the bottom than at the top, said channels extending through the periphery of the cover and opening into the space formed between the inner wall of the jar and the outer vertical face or wall of the cover. As will be noted upon reference to Fig. 1, the bottom of the chamber or receptacle 9 is inclined outwardly and downwardly, such inclination extending through the grooves or channels 10. Preferably, in order to produce a light structure and to somewhat restrict the chamber 9, the central portion of the cover will be provided with a recess 11, the outer wall of which forms one wall of the chamber 9.

When the jar is being used, the same will be filled to a point adjacent to the lowermost edge of the seat 2, and as the top or closure is inserted the rounded projection 4 first contacts with the material within the jar and tends to force the same laterally. The material will also be caused to rise within the jar and any air-bubbles will travel upwardly and outwardly along the inclined face 5, passing thence beneath the cover and out between the edge of the cover and the inner wall of the jar. When the cover comes to rest upon the seat 2 the sealing material may be poured into the chamber or reservoir 9 and will flow outwardly therefrom through the radially disposed grooves or channels 10 into the space between the cover and the wall of the jar, thereby sealing the same. In some instances the material within the jar may rise above the seat 2 to a slight extent, but if so it will be entirely covered by the sealing medium which fills the space left between the closure or cover and the wall of the jar. In any event, the sealing medium should contact with the contents of the jar so as to hermetically seal the same. The sealing material will preferably be of such depth

as to completely fill the grooves or channels 3 and the corresponding channels 6 and 7, though a tight seal may be secured where only one pair of oppositely-disposed grooves 5 is filled.

When it is desired to remove the cover, it is only necessary to run a knife or other sharp-pointed instrument into the groove or channel, cutting the paraffin or other 10 sealing medium, whereupon the cover may be lifted out; or if it tends to stick it may be pried off by passing a suitable tool below the upper wall of the channel 8, using the edge of the jar as a fulcrum. Or if desired, 15 heat may be applied to the upper part of the jar or vessel for a period sufficient to soften the sealing medium, after which the closure may be readily removed. The sealing material left within the reservoir 9 will 20 adhere to the cover and also fill the channels 10. When the cover is again used, after having been removed, the heat transmitted thereto from the material contained within the jar will tend to melt the sealing 25 medium contained in the chamber or reservoir 9 and thereby again seal the jar, without further attention on the part of the operator or attendant. When the material is packed cold it is, of course, necessary to 30 apply heat to the sealing medium to cause it to flow.

Having thus fully described my invention, what I claim is:

1. A jar provided with an internal seat 35 adjacent its upper end and a groove in the inner wall above said seat; combined with a closure, said closure being of a diameter to rest at its edge upon the seat in spaced relation to the inner wall of the jar, said 40 closure being formed with a groove around its edge and having a reservoir formed in its upper face, with an opening extending from the lower portion of said reservoir through the outer wall thereof.
2. A jar provided with an internal seat 45 adjacent its upper end and a groove in the inner wall thereof above the seat; combined with a closure having a reservoir in its upper face adapted to contain a sealing medium, said reservoir being in communication,

through openings in its outer wall extending into the lower portion of the reservoir, with the space formed between the edge of the closure and the adjacent wall of the jar when the closure is seated.

3. A jar provided with an internal seat 55 for a closure; combined with a closure adapted to rest upon said seat in spaced relation to the adjacent wall of the jar, said closure being provided with a reservoir, 60 adapted to contain a sealing medium, the lower portion of said reservoir being in communication with the space between the closure and the adjacent wall.

4. A jar provided with an internal seat 65 for a closure, located adjacent the upper end of the jar, and likewise provided with a groove upon the inner wall above the seat; combined with a closure adapted to rest upon said seat, said closure being formed 70 with an external groove or channel, and with a reservoir for sealing material in its upper face; said reservoir opening from the bottom outwardly through the outer wall thereof by a series of grooves or channels. 75

5. A jar provided with an internal seat for a closure, said seat inclining downwardly, the jar being likewise formed with an internal groove above the seat; combined with a closure, said closure having an upwardly and outwardly inclined bottom face, with a central depending rounded projection, said closure being likewise provided with a groove or channel about its periphery, and said closure being also formed with 85 a reservoir in its upper face adapted to contain a sealing medium, said reservoir being in communication with the grooves aforesaid and the space between the edge of the closure and the adjacent wall of the jar, 90 through channels formed in the outer wall of the reservoir.

In testimony whereof I have signed my name to this specification in the presence of two subscribing witnesses.

HARRY A. STEPHENS.
